UNITED STATES PATENT OFFICE.

BENEDICT FREY, OF NEW YORK, N. Y., AND HENRY LOGES, OF NEWARK,
NEW JERSEY.

VENT-FAUCET.

SPECIFICATION forming part of Letters Patent No. 429,433, dated June 3, 1890.

Application filed December 16, 1889. Serial No. 333,908. (No model.)

To all whom it may concern:

Be it known that we, BENEDICT FREY, of the city, county, and State of New York, and HENRY LOGES, of Newark, in the county of Essex and State of New Jersey, citizens of the United States, have invented certain new and useful Improvements in Vent-Faucets, of which the following is a specification.

This invention relates to an improved attachment to faucets for beer and other kegs, whereby simultaneously with the opening and closing of the faucet the vent-opening for the keg is opened and closed.

In the accompanying drawings, Figure 1 represents a vertical longitudinal section of a keg, showing our improved vent attachment and the faucet in position thereon. Fig. 2 is a side view of the faucet, drawn on a larger scale, showing the connection of the tap-plug of the same with the valved end of the vent-tube. Fig. 3 is a vertical transverse section of the faucet on the line 2 2, Fig. 2; and Fig. 4 is a vertical longitudinal section of the coupling by which the vent-tube is connected to its valved end.

Similar letters of reference indicate corresponding parts.

Referring to the drawings, A represents the faucet of a beer or other keg; B, the vent-plug of the same, and C a vent-tube, of rubber or other suitable flexible material, that connects the vent-plug B along the outside of the keg with the faucet, as shown in Fig. 1. The faucet A is made of the usual shape and material and provided back of its discharge-spout and head with a detachable or adjustable collar D, which is made of two sections d d, that are hinged together at one end and connected by a fastening-screw d', which passes through the lug d² at the opposite end, as shown in Fig. 3. One of the sections d is provided with a ring-shaped arm or standard D', that supports the valved front end C' of the vent-tube C. The front end C' is securely applied to the supporting-arm D' by means of a jam-nut d³, that is screwed up against said arm on the externally-threaded surface of the end C' of the vent-tube. The front end of the vent-tube C is provided in front of the arm D' with a valve or cock C², the handle of

which is applied to a slotted arm E, that is connected by an intermediate pivot-link e with a lever-arm E', that is applied by an adjustable collar e' to the tap-plug A' of the faucet A. The collar of the lever-arm E' is attached to the tap-plug A' by a clamp-screw e², that engages the end lugs of the collar e', so that the collar is tightly clamped to the tap-plug of the faucet. The vent-plug B is also provided with a stop-cock b, by which the vent may be closed—for instance, when the keg is to be kept over night, or when it is desired to remove the vent-tube and faucet. The vent-tube B is connected by a coupling F with the valved end C', the coupling being formed of flat sections f f, having registering vent-openings f' and an intermediate perforated washer between the faces of said sections, as shown in Fig. 4. The sections f f are tightly clamped together by a U-shaped clasp F', that is pivoted to one of the sections of the coupling, the clasp being provided with a lug for taking hold of the same in removing it from the sections f f or applying it thereto. The coupling F serves for the purpose of disconnecting the vent-tube from the valved end C', attached to the faucet, whenever the latter is to be removed from the keg for cleaning or other purposes, or when the keg is to be tapped. When the faucet is replaced, the connection between the valved end C' and the vent-tube C is re-established and the stop-cock of the vent-plug B opened. When the tap-plug A' of the faucet A is turned into open position, the lever-connection between the same and the valved end C' of the vent-tube C is operated, so as to turn the valve and move it into open position, and permit thereby the atmospheric air to enter through the vent-tube and vent-plug to the interior of the keg, so that the liquid in the same can be discharged through the faucet. When the tap-plug of the faucet is closed, the valve of the vent-tube is simultaneously closed, and thereby the admission of air to the interior of the keg prevented. In this manner the vent attachment is operated simultaneously with the opening and closing of the faucet in drawing off the liquid in the keg.

Our improved vent attachment for kegs has

the advantage that it can be readily applied to any faucet without requiring a faucet of any special construction. It can therefore be furnished at a low price, and can be applied 5 with great facility to the faucet and vent-plugs in common use, which is a great practical advantage for its introduction to specially-constructed vent-faucets.

Having thus described our invention, we 10 claim as new and desire to secure by Letters Patent—

A vent apparatus for barrels or kegs, consisting of an adjustable collar adapted for application to a tap-faucet and provided with 15 an arm, a vent-tube provided with a valve

and supported by said arm, a slotted arm for engaging the cock of said valve, an adjustable collar adapted for application to the tap-plug of said faucet and provided with an arm, and a pivot-link connecting said slotted arm 20 and the arm on the tap-plug collar.

In testimony that we claim the foregoing as our invention we have signed our names in presence of two subscribing witnesses.

BEN. FREY.
HENRY LOGES.
